(57) **CLAIM**

The ornamental design for a luminaire, as shown and described.

DESCRIPTION

FIG. 1 illustrates a bottom, front perspective view of a luminaire showing our new design;

FIG. 2 illustrates an alternate bottom, front perspective view thereof;

FIG. 3 illustrates a top, back perspective view thereof;

FIG. 4 illustrates a top, front perspective view thereof;

FIG. 5 illustrates a bottom, side perspective view thereof;

FIG. 6 illustrates a front elevation view thereof;

FIG. 7 illustrates a back elevation view thereof;

FIG. 8 illustrates a bottom plan view thereof;

FIG. 9 illustrates a top plan view thereof;

FIG. 10 illustrates a side elevation view thereof; and,

FIG. 11 illustrates an opposite side elevation view thereof. The broken lines are included for the purpose of illustrating portions of the article that form no part of the claimed design.

1 Claim, 10 Drawing Sheets(56)
